EXHAUST MANIFOLD FOR FOUR-CYCLE
INTERNAL-COMBUSTION ENGINES

Charles G. Barrett, Alexandria, Va.; Vera M. Barrett, administratrix of said Charles G. Barrett, deceased, assignor to Edward C. Magdeburger, Washington, D. C.

Application May 19, 1945, Serial No. 594,734

3 Claims. (Cl. 60—29)

1

This invention relates to exhaust manifolds for internal combustion engines and particularly four-cycle engines having six cylinders in line. Of course the engine may have more than one group of six cylinders in line, but an engine having one such group will suffice to illustrate the principle.

In designing an engine it is highly desirable that the connections for the exhaust of the respective cylinders be identical, and that the manifold be simple in form and compact. To avoid interference between exhaust flows from different cylinders, it has been proposed to provide distinct manifold passages, and to connect to any one such passage cylinders whose exhaust periods do not materially overlap. In a four-cycle engine, three cylinders can be connected to one passage without serious overlapping or interference provided their cranks are spaced at uniform intervals (i. e. 120° of crank angle).

A six-cylinder engine would thus require two distinct exhaust passages, and a convenient arrangement according to the invention is to have two passages, one of which serves cylinders 1, 2 and 3, and the other of which serves cylinders 4, 5 and 6. The firing order must be such that exhaust blasts to one passage alternate with exhaust blasts to the other passage. As a practical matter the firing order 1, 5, 3, 6, 2, 4 is the only one which will meet this requirement and still afford the best running balance. For this order the cranks align in pairs, as follows: 1 and 6; 2 and 5; 3 and 4.

The invention is intended for large engines, particularly compression ignition engines, and may or may not deliver the exhaust gases to a turbo-charger. It affords a comparatively light manifold which may be fabricated from plate and pipe by welding, which may be water cooled, which has a slender cylindrical configuration, and in which the two exhaust passages are so inter-related that the minimum avoidable resistance is offered to exhaust flow.

Stated in perhaps over-simplified terms, a cylindrical manifold shell is divided into two passages by a diametric plate which is twisted between the connections to cylinders 3 and 4, so that cylinders 1, 2 and 3 enter at one side of the plate and cylinders 4, 5 and 6 enter at the other side. The necessary amount of twist is a function of the diameters of the cylinder connections and the diameter of the manifold shell, but ordinarily is about 120°, and commonly is less rather than more. With conventional cylinder spacing, this affords a gradual twist. Except in the twist-

2

ed portion between the cylinders 3 and 4 the diametric plate is straight and extends from end to end of the manifold shell.

A preferred embodiment of the invention will now be described by reference to the accompanying drawings, in which:

Fig. 1 is a plan view of the complete manifold, with a terminal connection for a turbo-charger.

Fig. 2 is a section on the line 2—2 of Fig. 1. The cooling core and the divider plate are shown in elevation.

Fig. 3 is a fragmentary horizontal axial section on a larger scale than Fig. 1.

Figs. 4 and 5 are transverse sections on a still larger scale, the planes of section being indicated at 4—4 and 5—5 on Fig. 1.

Fig. 6 is an elevation of the right-hand end of the manifold.

Fig. 7 is a section on the line 7—7 of Fig. 6.

Fig. 8 is a perspective of the diametric divider plate showing the helical twist. Parts of the straight end portions are broken away to reduce the length of the view.

Fig. 9 is a fragmentary axial section on the same plane as Fig. 2, but drawn to a larger scale.

All statements of direction relate to the parts simply as they are shown in the drawings.

The manifold comprises two cylindrical shells, an outer jacket shell 11 and a coaxial inner shell 12 which is the manifold proper. The two are held in coaxial relation by a central pipe or water-core 13.

At the left-hand end (see Fig. 9) an annular head 14 connects the outer shell 11 and the water-core 13, and an annular head 15, spaced inward from head 14 connects the inner shell 12 and the water-core 13. At the right-hand end (see Fig. 7) an offtake fitting 16 having two exhaust connections 17 and 18 is connected to the outer shell 11, inner shell 12 and water-core 13. The last-named connection is through a part 19 of the divider plate, and a head 21 which closes the right-hand end of the water-core 13. All the joints mentioned above are welded.

The part 19 is the bridge part of a U-shaped flat plate 22 which straddles the right-hand end of the water-core 13 and divides the annular space between the parts 12 and 13 into two distinct passages which lead respectively to the connections 17 and 18. The two arms of plate 22 are continued, each by a helical plate 33 located at mid-length of the manifold and a straight flat plate 24 at the left-hand end of the manifold. The plate 22 is welded to plates 23 where their ends meet (see 25, Figs. 2 and 8), and the

latter to plates 24 where their ends meet (see 26, Figs. 2 and 8).

The plates 22, 23 and 24 are preferably welded continuously to the water-core 13 and shell 14 throughout their respective contacts, so that the two passages in the manifold are completely separated. An arcuate divider 21 (see Figs. 2, 3 and 7) is welded to parts 13, 23 and 12 to close one passage within the manifold. The left-end of water-core 13 is closed by cap 28. An inlet pipe 29 delivers cooling water to the far (right-hand) end and an off-take connection 31 assures return flow through the entire length of the core. Spacers 32 (see Fig. 3) help to hold core 13 centered.

Though the method of assembling and welding is not a part of the claimed subject matter of this application, it seems expedient to mention the preferred procedure. The water-core 13 is made up and the parts 23 are welded to it. Then a tube approximately coextensive in length with parts 23 and destined to form the middle part of shell 12 is slid over the helical parts 23 and welded thereto. Then the parts 22 and 24 are placed and welded to core 13 and to parts 23. The parts 22 and 24 are wider in a radial direction than are the parts 23, so the two end sections of the shell 12 are applied as the halves of a longitudinally split tube (see the welds 33 and 34 in Figs. 4 and 5). It follows that the cylindrical portion of shell 12 is actually made of five pieces welded into a unitary whole.

Three cylinder exhaust connections 37 are connected to openings in shell 12 to the left of the helical plates 23 and three cylinder connections 38 are located to the right of the helical plates 23. The six connections 37, 38 are identical and are uniformly spaced. Each has a connecting flange 39 and each is enclosed by a bonnet 41 which is welded to it and to the margin of a corresponding opening in outer shell 11.

The three connections 37 (assumed to be from cylinders 1, 2 and 3) lead to one passage in shell 12 and thence to connection 17, being deflected about 120° at the helical offset 23. The three connections 38 (assumed to be for cylinders 4, 5 and 6) enter the other passage which leads straight to connection 18. The left-end of this second passage is closed by plate 27, so that a portion of the second passage is unused. It is, however, considered simpler and better to have a complete cylindrical manifold, than to omit the unused left-end portion of this passage.

Pyrometer connections are shown at 42. Water connections for the jacket space between shells 11 and 12 are shown at 43, while vent and drain connections are shown at 44 and 45 respectively. Clean-out openings 46 with covers 47 are provided at intervals in shell 11, as indicated.

The grooved sleeves 48 receive split packing rings and seal expansion joints to the intakes of a turbo-charger, or to other appropriate exhaust connections.

Assuming a firing order of 1, 5, 3, 6, 2, 4, discharges will occur in strict alternation to the two connections 17 and 18 through the two manifold passages. There will be practically no cross flow since there is only negligible overlap of exhaust periods for either passage. The flow from cylinders 1 to 3 will be only slightly diverted, and the inclined arrangements of connections 37, 38 favors sustained flow.

Consequently the invention affords excellent exhaust flow characteristics in a light simple

structure having a very simple and neat cylindrical contour.

What is claimed is:

1. An exhaust manifold for a four-cycle internal combustion engine having six cylinders arranged in line and a firing order such that cylinders in the respective longitudinal halves of the row of six cylinders exhaust alternately, said manifold comprising an elongated generally cylindrical shell having lateral exhaust connections leading thereto; a partition extending from end to end of the manifold and substantially diametrically across the same to subdivide the manifold into two distinct longitudinal passages, said partition being helically displaced between the connections from the third and fourth cylinders sufficiently to cause the first, second and third exhaust connections to enter one passage and the fourth, fifth and sixth to enter the other, and means for closing the latter of said passages at a point between the connections leading from the third and fourth cylinders.
2. An exhaust manifold for a four-cycle internal combustion engine having six cylinders arranged in line and a firing order such that cylinders in the respective longitudinal halves of the row of six cylinders exhaust alternately, said manifold comprising an elongated generally cylindrical shell having lateral exhaust connections leading thereto; and a partition extending from end to end of the manifold and substantially diametrically across the same to subdivide the manifold into two distinct longitudinal passages, said partition being straight except between the connections from the third and fourth cylinders, and being there helically displaced sufficiently to cause the first, second and third exhaust connections to enter one of said passages and the fourth, fifth and sixth to enter the other.
3. An exhaust manifold for a four cycle internal combustion engine having six cylinders arranged in line and a firing order such that cylinders in the respective longitudinal halves of the row of six cylinders exhaust alternately, said manifold comprising an elongated generally cylindrical double walled shell having lateral exhaust connections for respective cylinders leading to the interior of the inner wall of the shell; a tube extending axially through the shell; diametrically arranged webs spanning the intervals between said tube and the inner wall of said shell connected to both and serving to divide the said interval into two distinct longitudinal passages, said webs being straight except between the connections for the third and fourth cylinders and there being deflected to cause the first, second and third exhaust connections to enter one of said passages and the fourth, fifth and sixth to enter the other; and water circulating connections for leading water to and from the space between the walls of said shell and to and from said tube.
